UNITED STATES PATENT OFFICE.

GOTTFRIED VON SÜSSKIND, OF ST. GEORGEN, SWITZERLAND.

HYDRAULIC PRESS FOR THICK FLUID SUBSTANCES.

SPECIFICATION forming part of Letters Patent No. 708,180, dated September 2, 1902.

Application filed February 24, 1902. Serial No. 95,467. (No model.)

To all whom it may concern:

Be it known that I, GOTTFRIED VON SÜSSKIND, a citizen of Germany, residing in St. Georgen, near St. Gallen, in the canton of 5 St. Gallen, Republic of Switzerland, (whose post-office address is St. Georgen, near St. Gallen,) have invented certain new and useful Improvements in Hydraulic Presses for Thick Fluid Substances; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

I have applied for patents in the following countries: application in Switzerland on 20 August 14, 1901; application in France on September 14, 1901; application in Germany on September 16, 1901; application in Italy on September 16, 1901.

The object of the present invention is a 25 hydraulic press for thick fluid substances, one form of construction of which is illustrated by way of example in the accompanying drawings, in which—

Figure 1 is a vertical section through the 30 center of the press. Fig. 2 is a plan view of the same. Fig. 3 is a horizontal section on the line $x-x$ of Fig. 1. Fig. 4 shows a horizontal section of a plate which can be heated by steam. Fig. 5 shows a vertical section of 35 a portion of Fig. 1 on an enlarged scale.

Upon the table 2, supported on standards 1, are screwed two strong posts 3 4. On the former is pivoted the center piece 5 of the receptacles 6 7, which together form one piece. 40 In the position illustrated the receptacle 7 rests with a projecting edge 10* over an aperture 9 in the table 2, which aperture is devised to receive a mold 8. In order to enable the two receptacles to be raised from the table, there is placed on the post 3 a double-walled cylinder 10, which is closed at the top and the cavity 13 of which is closed at the bottom by a packing 11. Set-screws 14 15 in the latter and supported on the table allow 45 of the correct moving up of the receptacles. The cylinder 10 has, moreover, a perforation 12, which communicates, on the one hand,

with the pressure-water tube 18 and, on the other hand, with the hollow chamber 13. By 55 passing the pressure-water into the hollow chamber 13 the cylinder 10 is raised, whereby the packing, by means of the set-screws 14 15, catches against the fixed table. After the receptacles have come out of engagement with the table they can be turned one hundred and eighty degrees around the post 3, so that receptacle 6 takes the place of receptacle 7, and vice versa. Stops 16 17, placed on the two receptacles 6 7, by striking against the post 4 limit the rotation of the receptacles. An angle-bar 18', placed on the stop 17, and a ball-bearing 55, set between the center piece 5 and cylinder 10, enable the rotation to be easily effected by hand.

On the upper part of the posts 3 4 is set 70 another pressure-cylinder 19, with piston 20, to which is linked a compressor 21 of corresponding section to the receptacles 6 7. Into the bore of the cylinder 19 the pressure-water tube 22 discharges, so that the piston 20 75 can be lowered by hydraulic power. To the top of the post 3 is pivoted a revoluble support 23, on the horizontal arm 24 of which are arranged two spindles 25 26, provided with screw-threadings which bear a piston 80 27, corresponding to the aperture of the receptacles 6 and 7. Between the two spindles 25 26 is arranged a fixed axle 28, on which the fly-wheel 30 revolves. The hub of the latter bears a wheel 31, which engages in two 85 gear-wheels 36 37, placed on the matrices 34 35, revoluble in the bearings 32 33 for the spindles 25 26, so that by suitably revolving the fly-wheel 30 the piston 27 can be raised or lowered. In the position illustrated the 90 receptacle 6 is closed below by a bottom piece 38, which is arranged in a support 41 on a screw-threaded spindle connected by a nut 40 with a fly-wheel 39.

The method of operation is as follows: The 95 mass to be pressed is placed in the receptacle 6, the support 23 having been previously rotated about ninety degrees, thus rendering the receptacle easily accessible. Then by turning the fly-wheel 30, and the consequent 100 lowering of the piston 27, the mass is so strongly pressed that after removing the bottom 38 it remains in the receptacle. After this the pressure-water is introduced through

the pipe 18 into the bore 13 of the cylinder 10, and thereby the two receptacles are raised until the edge 10* comes out of engagement with the table 2. By means of the bar 18' the filled receptacle 6 is then turned above the aperture 9 in the table, so that after letting off the water which was introduced into the cylinder 10 it takes exactly the position formerly held by the receptacle 7. By introducing the pressure-water into the cylinder 19 the piston 20, with the compressor 21, is made to descend, and thereby the mass in the receptacle 6 is pressed through the mold 8. While the compressor 21 is sinking in the receptacle 6, the receptacle 7 can be charged in the manner described above, so that continual working is possible. In order to prevent the two receptacles being lifted off the table by the pressure of the compressor 21, the two posts 3 4 are provided with screw-threadings 43 44 and nuts 45 46, which can be engaged by rotating a vertical bar 48, provided with a handle 47, from which bar the movement can be transmitted to the nuts 45 46 by means of levers 49 50 51 and 52 53 54, respectively, and thereby fix the central part 5 and stop 16 or 17.

The mold 8 (shown in Figs. 3 and 5) is adapted for making macaroni.

30 On a heel 55* of the funnel 56, which widens out toward the bottom, is a grating 57, strengthened by transverse bars. On this grating rests a bipartite metal plate 42, the outer form of which corresponds to that of the 35 grating 57. In the walls of each plate, as also in the ribs thereof, are two series of superposed steam-passages 59 60, the upper series communicating with the lower by means of a number of apertures 61 62. If now steam is 40 introduced through the two pipes 63 64 and let out again through the pipes 65 66, the two plates are uniformly heated and receive the mass pressed through the mold 8 warm and malleable. Above the metal plate 42 is the 45 plurally-divided mold 8, which has a number

of holes, each corresponding in size to the section of the macaroni. By means of screws the mold is secured to the metal plate 42. The receptacle presses with its lower edge upon the mold and assists in maintaining the same 50 in the recess of the table.

What I claim is—

1. In a hydraulic press for thick fluid masses, rotatable receptacles, a divided mold in communication with said receptacles, 55 means for lifting the said rotatable receptacles out of a recess in the table, mechanism for adjustably securing the receptacles to their support, and means for heating the mold and the substances under pressure. 60

2. In a hydraulic press for thick fluid masses, rotatable receptacles, a plurally-divided mold placed in the table and secured in position by the receptacles and screws, a hydraulic pressure device concentric to the 65 axis of rotation of the receptacles and adapted to lift the rotatable receptacles out of the recess in the table, means for adjustably securing the receptacles to their support, a perforated heating-body having a system of 70 passages and placed beneath the mold for heating the same and the substances under pressure.

3. In a hydraulic press for thick fluid masses, in combination the posts 3 and 4, the 75 center piece 5 the receptacles 6 and 7, the mold 8, the funnel 56, the plate 42, the grating 57, the steam-passages 59 and 60, the inlet-pipes 63 and 64 the outlets 65 and 66, mechanism for raising said receptacles 8 and mechanism for adjustably securing the receptacles 80 to their support.

In testimony that I claim the foregoing I have hereunto set my hand this 11th day of February, 1902.

GOTTFRIED VON SÜSSKIND.
